Attorneys.

UNITED STATES PATENT OFFICE.

ROBERT L. PORTER, OF LOS ANGELES, CALIFORNIA.

WIRE-ROPE DRILLING CLAMP.

Application filed November 20, 1924. Serial No. 751,134.

To all whom it may concern:

Be it known that I, ROBERT L. PORTER, a citizen of the United States, residing at Los Angeles, in the county of Los Angeles and 5 State of California, have invented new and useful Improvements in Wire-Rope Drilling Clamps, of which the following is a specification.

This invention relates to well drilling outfit 10 fits and more particularly to wire rope or steel cable clamps used in connection with the temper screws of standard drilling rigs. The object of this invention is to provide a cable clamp having friction means that 15 continuously engage the cable in such a manner that the cable may either be gripped or released, said means adapted to move with the cable when released so that the cable will not be damaged from contacting with 20 relatively stationary surfaces.

Another object is to provide a clamp of the character referred to which is simple in construction, easily operated, and which may be quickly connected to the temper 25 screws.

These objects are attained by the disclosure herein set forth by the following description of the accompanying drawings, the novel features thereof being set forth in the 30 appended claims, in which

Figure 1 is a front elevation of the cable clamp connected to a temper screw.

Fig. 2 is a horizontal section taken on the line 2—2 of Fig. 1.

Fig. 3 is a transverse section taken on the 35 lines 3—3 of Figs. 1 and 2.

Fig. 4 is a transverse section taken on the line 4—4 of Fig. 2.

Referring by numerals to the drawings, a 40 cable clamp constituting the invention is generally designated at A, having clamping members 10 and 11. The clamping member 10 has a jaw portion 12 in which is formed an opening 13 and a channel 14 communicating with the opening. The channel has parallel sides 15 which are at right angles to walls 16 in the opening 13. The opening 13 has side walls 17 and an end wall 18 terminating in a tapered portion 19. The 45 side walls 17 have inwardly projecting offset portions 20 having horizontal surfaces 21 and vertical side faces 21', the vertical faces 21' being flush with the side walls 15 of the channel 14.

Integrally formed on the jaw portion 12

is an arm 22, a lug 23 and an ear 24. A recess 25 is formed in the lug 23 and a vertical bore 26 extends through the lug on each side of the recess. An aperture 27 is formed in the ear 24 to receive a link 28. 60

The clamping member 11 is of substantially the same construction as the clamping member 10, having a jaw portion 12' in which is formed an opening 13' and a channel 14' communicating with the opening. 65 The channel has parallel sides 15' which are at right angles to walls 16' in the opening 13'. The opening 13' has side walls 17' and an end wall 18' terminating in a tapered portion 19'. The side walls 17' have inwardly projecting offset portions 20' having horizontal surfaces 21' and vertical side faces 21'', the vertical faces 21'' being flush with the side walls 15' of the channel 14.

Integrally formed on the jaw portion 12' 70 is an arm 22', lugs 29 and 30, and an ear 31 having an aperture 32 adapted to receive a link 33.

Friction means adapted to engage a cable 75 generally designated at C consists of an endless link chain 34 carried by a member 35 and an endless link chain 34' carried by a member 35'. The chains 34 and 34' are composed of links L and L' connected by pins, the links L having concave faces F and curved ends E. The member 35 has parallel sides 36, a curved top 37 and a flat bottom 38. In a like manner, the member 35' has parallel sides 36', a curved top 37' and a flat bottom 38'. The member 35 is mounted 80 in the opening 13, the bottom 38 resting on the surfaces 21 and the chain 34 carried by the member 35 engaging the sides 15 of the channel 14. The chain 34' and the member 35' are mounted in the opening 13' and 85 channel 14' in the same manner as the chain 34 and member 35. The chains 34 and 34' are pressed inwardly by leaf springs 39 engaging the members 35 and 35'. An eye bolt 40 fits in the recess 25 in the lug 23. The lug 23 of the clamping member 10 and the lugs 29 and 30 of the clamping member 11 overlap and are pivotally connected by a pin 41 passing through the bore 26 in the lug 23 and bores 29' and 30' in the lugs 29 90 and 30 and a hole 40' in the eye bolt 40. 100

A nut 42 having an annular groove 43 engages the threaded end of the eye bolt 40, and a collar 44 engages the groove 43 and 105 is connected to the arms 22 and 22' by links 110

43 and bolts 46. The clamp A is connected to a temper screw S by the links 28 and 33, as shown in Fig. 1.

From the construction it will be seen that 5 the chains 34 and 34' continuously engage the cable C, due to the pressure exerted by the leaf springs 39 through the members 35 and 35', the concave faces F of the links L conforming to the diameter of the cable, 10 and the links L engaging the sides of the channels 14 and 14'. As clearly shown in Fig. 2, the cable is gripped by the clamping members 10 and 11 at which time the members 35 and 35' are pressing against the 15 chains 34 and 34', this pressure being effected by rotating the nut 41 to the right.

When it is desired to release the cable, the nut 41 is turned to the left, which will cause the jaws to open, thereby releasing 20 the tension on the cable, the chains, however, remaining in contact with the cable due to the action of the leaf springs 39, and when the cable is moved in either direction 25 the chains will move with the cable over the members 35 and 35'.

It will be noted that the endless chains present considerable surface engaging the cable and move with the cable (when not gripped), thus preventing damage and 30 wear on the cable.

Various changes may be made without departing from the spirit of the invention as claimed.

What is claimed is:

35 1. A cable clamp comprising a pair of pivotally connected clamping members, said clamping members having jaw portions, each of said jaw portions having an opening, an endless link chain mounted on 40 a member movable within each opening, expansion springs within each opening engaging each member, and means for opening and closing said jaws.

45 2. A cable clamp comprising a pair of clamping members, each of said clamping members having jaw portions, arms projecting from said jaw portions, a pair of lugs formed on one of said jaw portions and a single lug formed on the second jaw portion, said second jaw portion having a recess within said lug, an eye bolt mounted within the recess of said second jaw portion, said eye bolt having a nut mounted on the threaded portion thereof, a collar carried by said nut, links connecting said collar and said arms of the jaw portions, said 50 lugs of the jaw portions inter-locking, a pivot pin extending through the bores in said lugs and eye bolt, each of said jaw portions having an opening, a channel cut in

the inner side of each jaw portion and communicating with said openings, a member movable within each opening, link chains mounted on said members, expansion springs engaging said members, an ear 65 formed on each of said clamping members, an opening formed in each of said ears, and a link in each of said ears adapted to support the cable clamp on a temper screw.

3. A cable clamp comprising a pair of 70 clamping jaws, members slideable upon said jaws, and endless chains passing around said members adapted to engage upon a cable:

4. A cable clamp comprising a pair of 75 clamping jaws, members slideable upon said jaws, endless chains passing around said members adapted to engage upon a cable, and spring means for urging said members toward each other.

5. A cable clamp comprising a pair of clamping jaws, members slideable upon said jaws, and endless chains passing around said members, said members being so arranged that when the adjacent sides of said 85 endless chains are clamped upon a cable, said members will cooperate with their respective jaws to clamp the remote sides of said endless chains therebetween.

6. A cable clamp comprising a pair of 90 clamping jaws, members slideable upon said jaws, endless chains passing around said members, said members being so arranged that when the adjacent sides of said endless chains are clamped upon a cable, said members will cooperate with their respective jaws to clamp the remote sides of said endless chains therebetween, and spring means for urging said members toward each other.

7. A cable clamp comprising two jaws and an eye-bolt pivoted together, arms carried by said jaws and disposed at the sides of the eye-bolt, a nut threaded onto the eye-bolt, a collar upon the nut, and links connecting said collar to said arms, whereby movement of said nut will cause said jaws to be clamped together or to be separated from each other.

8. In a cable clamp, a pair of jaws, members movable upon said jaws, and endless chains passing around said members and being so arranged that when the adjacent sides of said chains are clamped together upon a cable, other portions of said clamp will also be clamped between said members and portions of their respective jaws.

In testimony whereof I have signed my name to this specification.

R. L. PORTER.
